WALL-HUNG CLOSET CARRIER

John E. Svabek, Jr., Chicago, Ill., assignor to Crane Co., Chicago, Ill., a corporation of Illinois

Application November 16, 1953, Serial No. 392,251

6 Claims. (Cl. 4—252)

This invention relates to an improved carrier for the bowl of wall hung water closets.

To obtain a better appreciation of the improvements contributed to the art by the present invention, the following should be borne in mind.

Heretofore, the design of wall hung closet carriers necessitated a final adjustment of the carrier supporting structure both behind and in front of the finished wall. The final step in the installation of the water closet is of the utmost importance, as proper closet support eliminates the placing of any undue stress on the soil pipe, or extension thereof, and the finished wall. It is obvious that the proper adjustment can be effected only with the exercise of painstaking care in the limited space behind the finished wall. The inability to make a proper adjustment in the confined wall spaces as demanded by the prior carrier designs has resulted in undue stresses being imparted to both the wall and the plumbing connection as well.

It is therefore a main object of my invention to present a carrier which is simple in design and which can be mounted on the face of the finished wall requiring no final adjustment behind the wall.

It is a further object of my invention to provide a carrier design which is composed of basic parts which are relatively simple to assemble and manufacture, thus assuring both ease of installation and a low unit cost.

These and other objects of my invention will become more readily apparent upon proceeding with the following detailed description read in the light of the accompanying drawings, in which

Fig. 1 is a perspective exterior view of the closet carrier which is the subject matter of my invention.

Fig. 2 is a perspective view of a soil pipe connected to the novel closet carrier.

Fig. 3 is a side elevation, partly in section, of a closet utilizing my invention.

Similar reference numerals refer to similar parts throughout the several views.

Referring now to Fig. 1, a wall plate 1 is illustrated which is preferably of rectangular or other polygonal configuration. The plate 1 is tapped at 2 for threadedly engaging a soil pipe nipple 14 (see Fig. 2). The four edges of the plate are tapped as at 3 for purposes of having the upright supporting arms 4 attached thereto by means of the bolts 5. It will be noted that by tapping all four edges of the wall plate 1, the carrier will be in proper position for complete assembly on approaching the wall surface after every quarter turn of the plate on the soil pipe nipple. It should be understood that the ability of the plate to properly position with every quarter turn presents a novel and distinct advantage in that a close and more efficient adjustment is possible relative to the finished wall.

The supporting arms 4 are provided with tapped holes 6 for threadedly engaging studs 7 which are the means for supporting the closet 13 as shown in Fig. 3. The washers 10 and cap nuts 17 which threadedly engage the termini of the studs 7 firmly secure closet 13 in position.

2

The arms 4 are also provided with drilled holes 8 shown in Fig. 3 for purposes of assembly to the wall plate 1 by means of the bolts 5. The lower portion of the supporting arms 4 are obliquely tapped as at 9 for threadedly engaging headless set screws 11. It is the action of the termini of these screws bearing against the surface of the angle iron 12 or other fixed abutment behind the wall which transmits the stress of the suspended closet from the carrier as shown in Figs. 2 and 3. In addition, the screws 11 provide stability of the entire assembly as rotation of the closet and attached carrier about the threads of the soil pipe nipple 14 is prevented by their opposed positioning, as is clearly depicted in Fig. 2.

Referring now particularly to Fig. 3, a closet bowl 13 is illustrated, partly in section, utilizing my invention. The wall plate 1 is depicted threadedly engaged to the soil pipe nipple 14, which is in turn threadedly engaged to the soil pipe fitting 20. Interposed between the nipple 14 and the end surface 15 of the closet 13, the gasket 16 made of rubber or other suitable gasket material is positioned. It will be noted that the end surface 15 and the flange portion 18 of the closet 13 define a recess 19 for receiving the entire carrier assembly. The closet flange portion 18 conceals the carrier from view in the final assembled position, thereby presenting a pleasing appearing closet design which is substantially close to the wall W at its end limit.

Particular attention is now directed to the supporting headless set screws 11 which penetrate the wall W 30 through the oblique passages 21. As illustrated, the end limits of the screws 11 bear against the angle iron 12 which is maintained in a stationary position behind the wall W by means of the screws 22 which fasten the iron 12 to the floor F. It is, of course, obvious that any 35 equivalent means may be substituted for the angle iron 12, such as a recessed block positioned behind each wall passage 21, which will function to similar advantage.

From Figs. 1 and 2, it is apparent that the oppositely disposed positioning of the screws 11 on the supporting 40 arms 4 will prevent any applied force on a side edge of the bowl 13 from causing the bowl and attached carrier to revolve about the waste pipe threaded connection at 2.

Prior to final assembly of the closet 13 to the carrier by means of the studs 7 and cap nuts 17, the supporting arms 4 and attached wall plate 1 are set in fixed relation to the angle iron 12 by adjusting the supporting screws 11. The adjustment comprises the simple act of advancing the screws 11 through the tapped holes 9 by means of a screw driver until the screw ends are firmly positioned against the angle iron 12. The closet bowl 13 is then firmly secured to the supporting arms 4 by means of the studs 7 which pass through the holes 23 of the closet bowl. The washers 10 and cap nuts 17 are then assembled to the ends of the studs 7.

From Figs. 2 and 3, it will be noted that the downward thrust imparted to the carrier by the closet bowl 13 is reacted to and negated by the set screws 11 reacting on the angle iron 12. Consequently, a stable, secure assembly is effected employing my carrier with an ease of installation heretofore unknown.

It should be appreciated that by utilizing my invention no final adjustment behind the wall is necessary. The edge of the angle iron 12, or other fixed abutment, is positioned immediately behind the finished wall beneath 65 the soil pipe nipple 14 and may therefore be easily installed on the floor surface prior to the erection of the finished wall W. After the erection of the wall W, the set screws 11, as previously described, are made to bear against the angle iron 12. This simple adjustment is performed from the outside of the wall and obviates any necessity for adjusting a soil pipe support or other reinforcing means behind the wall W.

It should be further noted that the carrier assembly may be advantageously employed with a blow-out type closet bowl. Since the soil pipe connection would of necessity be positioned higher relative to the floor than in a siphon closet installation as hereinabove described and illustrated, the supporting arm members would be attached to the wall plate at their upper extremities. It would therefore be possible to have supporting arms which would work equally well on blow out and siphon type closet bowls by merely obliquely tapping both ends of the supporting arms to engage the supporting set screws. Consequently, whether the wall plate is attached to the upper or lower extremity of the supporting arm would be immaterial since the set screws may be inserted and will perform their supporting function in either wall plate 15 position.

Thus, I have presented in the illustrated designs a wall hung closet carrier in which the final adjustment of the carrier is simply and effectually made on the outside of the finished wall eliminating the necessity of working in 20 confined walled-in spaces. In addition, efficient distribution of the downward thrust of the suspended closet to the floor behind the wall is effected with no stress imposed on the wall W itself. The set screw members transmitting the downward thrust perform the secondary function of stabilizing the closet bowl 13 against any revolution occasioned by a moment of force about the soil pipe connection resulting from a weight applied to an edge of the closet bowl. Thus, a secure closet assembly 25 is assured.

It is, of course, obvious to those skilled in the art that numerous substitutions and changes may be made in the details of the construction revealed without departing from the spirit of my invention as determined by the appended claims.

I claim:

1. In a closet carrier for a wall mounting substantially as described, the combination comprising a wall plate for mounting on a vertical finished wall or the like, the said wall plate having means cooperating therewith exteriorly accessible and adjustable relative to the wall plate and to said finished wall, said latter cooperating means comprising two upright supporting arm members removably attached to said wall plate, one of each of said arm members being mounted closely on oppositely disposed edge portions of said wall plate, said wall plate being substantially centrally apertured for connection to a soil pipe, a plurality of bolts mounted on the arm members and cooperating with said arm members to effect said removable attachment of the arm members to the wall plate edge portions, set screws partially slotted and threaded projecting through the arm members, said arm members engaging said set screws and having attachment means comprising studs cooperating with a forward face thereon whereby a plumbing closet or the like may engage and be supported by said studs and arm members, said arm members being obliquely tapped for threadedly engaging slotted end portions of said set screws to permit said projection therethrough, the inner termini of said slotted threaded set screws traversing a surface of the finished wall to extend therethrough and abut a fixed lower surface behind the said wall whereby the stress imparted to said supporting arm members by the closet is transmitted to the said fixed surface by the said set screws, all of said carrier elements above recited being accessible and adjustable from an exterior surface of the finished wall.

2. In a closet carrier for a wall mounting substantially as described, the combination comprising a wall plate mounted on a soil pipe or the like to substantially abut against a finished wall, the said wall plate having means exteriorly accessible and adjustable transversely relative to a finished wall, the said adjustable means including two supporting arm members, one of each of the latter being removably attached on side surface portions to said wall plate, said wall plate being predeterminately rotatable on

10
15

the soil pipe in the course of attachment to the said arm members and substantially of polygonal configuration in plan, the said wall plate being apertured for threaded connection to the soil pipe, a plurality of bolts cooperating with said arm members to hold the latter to the side surface portions of the wall plate, at least some of the surfaces defining the polygonal configuration of the wall plate being arranged with recessed portions to cooperate with the supporting arm bolts, set screws partially slotted and threaded carried by the arm members, said arm members recessed portions engaging said bolts and having stud attachment means thereon whereby a plumbing closet or the like may be supported by said stud attachment means of said arm members on front surfaces thereof, said arm members being obliquely tapped on a front surface thereof for threadedly engaging slotted portion of said set screws, the termini of said slotted threaded set screws traversing an apertured portion of the finished wall and abutting a fixed surface behind the said wall whereby the stress imparted to said supporting arm members by the closet is transmitted to the said fixed surface through the set screws, all of said carrier elements above recited being accessible and adjustable from an exterior front surface of the finished wall.

3. In a closet carrier for a wall mounting substantially as described, the combination comprising a wall plate mounted over an apertured portion of a wall, the said wall plate having means exteriorly accessible and being adjustable transversely relative to a finished wall, the said wall plate adjustable means including two supporting arm members each of which is removably attached to said wall plate on opposite side limits thereof, said wall plate being apertured for effecting a rotative connection to a soil pipe projecting through the wall, a plurality of bolts cooperating with sides of said arm members to attach the latter members to the wall plate, set screws substantially fully threaded carried by the arm members, said arm members, said arm members engaging said set screws and having stud attachment means thereon whereby a plumbing closet or the like may be mounted on the said arm members, fluid sealing means on the carrier between the soil pipe and the closet, said arm members being obliquely tapped for threadedly engaging said fully threaded set screws, the termini of said fully threaded set screws traversing an apertured surface of the finished wall to abut a fixed surface behind the said wall whereby the stress imparted to said supporting arm members by the closet is borne by the said fixed surface, the said supporting arms and wall plate being held against rotation around the soil pipe by the said fully threaded set screws abutting said fixed surface behind the wall.

4. In a closet carrier for a wall mounting substantially as described, the combination comprising a wall plate fitted over an apertured finished wall to receive a soil pipe connection, the said wall plate having means exteriorly accessible and adjustable relative to the finished wall, a fixed member behind the wall, the said wall plate adjustment means including two substantially vertical arm members removably attached to edges of said wall plate, said wall plate being substantially centrally apertured for connection to the soil pipe through the wall, a plurality of bolts cooperating with said arm members to attach the arm members to the sides of the wall plate, set screws carried by said arm members of a predetermined length permitting substantially complete entry within the combined wall plate and the finished wall, said arm members engaging said set screws and having threaded attachment means thereon whereby a plumbing closet or the like may be carried by said arm members, said arm members being obliquely tapped for receiving said set screws, end portions of said set screws entering predeterminately located transverse apertures on the finished wall and extending therethrough for abutting an inclined surface on said fixed member whereby the stress imparted to said supporting arm members by the closet is carried by the said

55

fixed member through the set screws of predetermined length.

5. In a closet carrier for a wall mounting substantially as described, the combination comprising a wall plate on an apertured wall for communication with a closet soil pipe or the like, the said wall plate having means exteriorly accessible and adjustable relative to a finished wall, the said wall plate adjusting means including two supporting arm members each of which is removably attached to opposite edges of said wall plate, said wall plate being apertured for rotatable attachment to the soil pipe, a plurality of bolts cooperating with said arm members for said removable attachment of the latter members to the wall plate, a fixed member cooperating with the back of the finished wall, set screws carried by said supporting arm members and being headless and of a length permitting their reception endwise within and through the wall plate, said arm members engaging said bolts and having threaded attachment means on a front face portion whereby a plumbing closet or the like may be hung from said arm members, said arm members being obliquely tapped for threadedly engaging end and median portions of said set screws, the ends of said headless set screws traversing a surface of the finished wall and abutting an inclined surface of the fixed member behind the lower portion of the said wall whereby the stress imparted to said supporting arm members by the closet is transmitted to the said fixed surface, the headless screws cooperating with the fixed member to align the closet properly relative to the wall and being concealed by the said closet when the latter is assembled on the carrier and against the finished wall.

6. In a closet carrier for a wall mounting substantially as described, the combination comprising a wall plate for positioning on an apertured finished wall, the said

10
15
